UNITED STATES PATENT OFFICE.

REGINALD A. FESSENDEN, OF WASHINGTON, DISTRICT OF COLUMBIA, ASSIGNOR TO
THE NATIONAL ELECTRIC SIGNALING COMPANY, OF PITTSBURGH, PENNSYLVANIA,
A CORPORATION OF NEW JERSEY.

RECEIVER FOR ELECTROMAGNETIC WAVES.

1,022,539.

Specification of Letters Patent.

Patented Apr. 9, 1912.

Application filed May 4, 1904. Serial No. 208,393.

To all whom it may concern:

Be it known that I, REGINALD A. FESSENDEN, a citizen of the United States, residing at Washington, in the District of Columbia, 5 have invented certain new and useful Improvements in Receivers for Electromagnetic Waves, of which the following is a specification.

My invention relates to receiving devices 10 of the type in which the currents to be detected, and also the current from a local circuit, both flow through a minute cross-section of fluid, and the energy of the currents to be detected causes a variation in the amount 15 of current in the local circuit.

The theory of the action of this radically new type of receiver, so far as it has been analyzed by the applicant, is given in U. S. Patent Reissue No. 12,115.

20 The invention will be more fully understood from the following description and claims taken in connection with the accompanying drawing, in which—

Figure 1 is a vertical section of one form 25 of a cell embodying my invention; Fig. 2 a vertical section of another form of electrode; Fig. 3 a vertical section showing an embodiment of my invention including parts particularly adapted for use with the form 30 shown in Fig. 2; Fig. 4 is a top plan view of the arrangement shown in Fig. 3, and Fig. 5 illustrates a modification of my improvement.

The receivers shown in said drawings 35 embody a characteristic feature of the receivers of said prior patent Reissue No. 12,115, in that in them the current is caused to flow through a very small cross-section of fluid. In most of the forms described in 40 said patent, this small cross-section is regulated by regulating the depth of immersion of a fine wire in a liquid, but in some forms, as for example that of Fig. 8 of said patent, the immersion is determined definitely by 45 causing the electrode to project a determined amount from a fine glass tube in which it is sealed.

In the device forming the subject-matter 50 of this application, the electrode 1 which is in the glass tube may preferably be ground off so as to be practically level or flush with the surface of the material in which it is sealed or held, the current flowing through

the minute cross-section of liquid contacting with the ground-off cross-section of the end 55 of the conducting electrode. This electrode should not be in close proximity to the other electrode, as thereby capacity effects would be produced which would result in a storing up of energy which would then become un- 60 available for producing an indication. In order to avoid any possibility of rectifying the currents which are to be detected, the voltage on the local circuit should be so high that a current flows continuously, and not 65 merely when the currents to be detected are passing, as is the condition in rectifiers by reason of the impressed voltage being lower than the decomposition of the electrolyte. Furthermore the electrode 1 and the other 70 electrode 4 should be so arranged that the lines of current flow spread out in a radial direction from the electrode 1, and thereby localize the effective resistance in the immediate neighborhood of the terminal of the 75 electrode. Also it is advisable to arrange the electrodes at a distance apart at least many times the diameter of the wire at 1.

In Fig. 1 the electrode 1 is sealed in the glass 2 and ground off flush, and is placed 80 near the bottom of a small glass vessel 3, and projecting upward, the other electrode 4 also being immersed in the liquid. I prefer to arrange the ground-off surface of the terminal of electrode 1 in a horizontal position 85 within the body of the liquid, directed toward the surface thereof, and also arranged at the apex of a projection as shown. One object of this is to permit the free detachment of any gas that may form on the 90 terminal, by reason of the buoyant effect of the gas.

Very much the same function can be 95 served by utilizing the arrangement of Fig. 2, sealing the whole electrode sheath into the body of the vessel 3 in place of the conical projection 2 shown in said Fig. 1. The device of Fig. 2 referred to is a small glass tube of an internal diameter of about .005 100 of an inch with a platinum wire .005 of an inch sealed into the ends and one end ground flush with the glass so that the wire is exposed only on its end surface. In Fig. 1 the larger electrode is formed by a wire 4, preferably platinum, sealed in the walls of the 105 vessel 3 so as to be below the electrode 1.

Its inner end is formed as a ring and surrounds the projection 2 which is preferably conical. In this construction any gas bubbles formed will float up from the ring 4 and thereby start a circulation in the liquid up through the center of the liquid and down along its sides. The construction shown in Fig. 1 gives highly uniformly good results.

10 The glass tube with the flush terminal thus formed is shown in Figs. 3 and 4 as mounted by clamping in a supporting bracket 5 by spring clip 6. This bracket is pivotally secured at 7 on the end of an arm

15 8, rotatably and longitudinally adjustable in a head 9 in which it is secured by screw 10. The mounting 9 is also adjustably fixed on a vertical post 11.

10 The ground off tip or terminal of the 20 electrode terminal 1 is arranged adjacent to a disk 12 of conducting material, preferably brass, having clamped thereon by the clamping ring 13 a moisture-retaining covering 14, preferably composed of an inner layer of 25 absorbent material and an outer layer of soft material such as cotton velvet. This disk 12 is mounted upon a shaft 12^a driven by clock work 15 through an intermediate rubber coupling 16 to prevent transmission 30 of vibration or shock from the clock work to the disk.

15 The terminal of electrode 1, as in Fig. 1 or Fig. 3, is immersed in an electrolytic or conducting solution which may be preferably dilute caustic potash or dilute nitrate or carbonate of soda; these may be mixed with glycerin to prevent evaporation and crystallization.

20 The usual receiving circuit leads are connected to the binding posts 17 and 18. The post 18 is clamped in any desired angular adjustment by means of the thumb nut 19, and this adjustment is used to vary the tension of a spring contact 20 leading to a 45 sleeve 21 on shaft 12^a.

25 Rotation of the disk 12 tends to brush or wipe away the minute gaseous formations tending to form on the terminal of electrode 1. As shown the disk supports a surface of 50 soft material moistened with the electrolyte, but it is obvious that the device may be arranged the same as shown in Fig. 3 with a receptacle containing a considerable amount of liquid substituted for said moistened surface 14. Thus arranged, the travel of the liquid past the terminal would tend to carry off bubbles after the same manner, though not so positively, as the cotton velvet described above. The object of both devices, 55 as well as the tapering of the sheath in Figs. 1 and 2, is to prevent the accumulation of gases on the terminals.

60 By the use of the present invention a larger wire may be used without increasing the area in contact with the fluid, because

only the end of the wire is exposed, and the terminals of the electrodes are so arranged as to permit of the radial or hemispherical spread of the line of current flow upon which depends the localization of the effective high resistance in the neighborhood of the exposed terminal. 70

As an alternative form the glass tube containing the sealed electrode terminal may be mounted upon an arm on a vertical rod and 75 revolved in a bath of solution so that here again the friction of the liquid against the exposed terminal will remove any gas which may form thereon, as shown in Fig. 5.

Wire of platinum-iridium may be used instead of platinum as being less liable to 80 occlude gas bubbles.

No claim is made herein to the specific construction shown in Fig. 5 as the same forms the subject-matter of a co-pending application filed March 26th, 1907, Serial No. 364,626, (Patent No. 917,574, of April 6th, 1909). 85

Claims:

1. A receiver for wireless telegraphy comprising a cell having an electrode terminal immersed therein, said terminal being exposed only on its end surface, and means to prevent accumulation of gas thereon, substantially as described. 90

2. A receiver for wireless telegraphy comprising an electrolytic cell having an electrode immersed therein consisting of a wire having a sheath covering it except on its end surface, and means to effect continual removal of bubbles of gas tending to accumulate on the terminal of said electrode. 100

3. A polarization cell adapted as a detector for wireless telegraphy having one electrode sheathed in non-conducting material except on its end surface, and another electrode of larger surface placed in the liquid of the cell below the level of the first electrode. 105

4. The combination of a support having a detachable terminal secured thereto and consisting of a conical non-conducting sheath with a conductor extending therethrough, and means for maintaining a moving body of liquid electrolyte in contact with the terminal of said electrode. 115

5. As an article of manufacture a detachable electrode for wireless telegraphy receivers consisting of a wire sealed in the point of a tapering non-conducting sheath 120 and exposed only on its end surface at the pointed end of said sheath.

6. As an article of manufacture, a detachable electrode for wireless telegraphy receivers consisting of a fine platinum wire 125 sealed in a glass tube, the said tube being tapered to a point and covering the wire except on its end surface, substantially as described.

7. As an article of manufacture, a detach- 130

able electrode for an electrolytic cell for use as a receiver in wireless telegraphy, consisting of a glass tube tapered to a fine point and a wire sealed in said tube and exposed 5 only at the point thereof on a minute area, and provided with a larger leading in wire connected to said terminal wire in the tube.

8. A receiver for wireless telegraphy comprising a fine point electrode and a liquid 10 electrolyte, and means for maintaining the two in relative motion whereby to remove bubbles from the electrode.

9. A receiver for wireless telegraphy comprising an electrode sealed in glass, and a 15 yielding material in contact with the electrode, and means for relatively moving the electrode and said material continually during use.

10. In a receiver for wireless telegraphy, 20 the combination with a fine point electrode, of a porous material moistened with a liquid electrolyte and means for maintaining it in movable contact with the electrode.

11. In a receiver for wireless telegraphy, 25 the combination with a fine point anode, of a cathode consisting of a vessel supporting a liquid electrolyte and means maintaining the electrolyte and anode in relative movement.

12. In a detector of electromagnetic waves 30 or other feeble electrical impulses, the anode of a polarization cell consisting of a fine wire surrounded by insulating material except on its end surface, such insulating material tapering to a fine point at the end of 35 the wire and the wire presenting a minute surface to the electrolyte.

13. A support, means for maintaining liquid electrolyte in operative relation thereto and a detachable terminal secured to said 40 support, consisting of a fine wire and a coni-

cal or converging sheath or tube, the portion of the sheath about said terminal being ground off.

14. A support, means for maintaining liquid electrolyte in operative relation thereto and a detachable terminal secured to said support, consisting of a conical or converging non-conducting sheath or tube and a fine terminal sealed in said conical or converging sheath, said sheath and terminal being 50 ground off flush with each other.

15. A receiver for wireless signaling comprising an anode of small area, a liquid electrolyte in contact therewith and means for relatively moving the anode and electrolyte. 55

16. In a receiver, a fine terminal, a suitable receptacle for a liquid electrolyte and means for causing relative movement of said terminal and receptacle.

17. A non-conducting sheath, a minute 60 anode and means for circulating a liquid electrolyte in contact therewith.

18. In a receiver, a non-conducting sheath, a fine terminal sealed therein and means for maintaining and changing a supply of liquid 65 electrolyte in contact therewith.

19. In a receiver, for wireless signaling, a fine point terminal, a support for liquid electrolyte and means for producing relative movement of said parts. 70

20. A receiver for wireless signaling comprising a fine point anode, a support containing a liquid electrolyte in contact therewith and means for relatively moving said support and said anode.
